The ornamental design for an absorbent pad, as shown and described.

DESCRIPTION

FIG. 1 is a top plan view of an absorbent pad, showing my new design;

FIG. 2 is a bottom plan view thereof;

FIG. 3 is an end elevational view thereof;

FIG. 4 is an end elevational view thereof, opposite that shown in FIG. 3;

FIG. 5 is a side elevational view thereof, the opposite side elevational view being identical; and,

FIG. 6 is a top isometric view thereof.
